CLAIM

The ornamental design for a ventilation fan as shown and described.

DESCRIPTION

FIG. 1 is a perspective view showing a first embodiment of a ventilation fan showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view showing a second embodiment of a ventilation fan showing our new design in a condition of use;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof; and,
FIG. 14 is a bottom plan view thereof.
The gray shading represents illumination.

The broken lines shown in the drawings illustrate portions of the article and form no part of the claimed design.

1 Claim, 14 Drawing Sheets
